UNITED STATES PATENT OFFICE.

ROBERT E. L. JANNEY, OF CHICAGO, ILLINOIS, AND EDMUND P. KINNE, OF ALLIANCE, OHIO, ASSIGNORS TO AMERICAN STEEL FOUNDRIES, OF NEW YORK, N. Y., A CORPORATION OF NEW JERSEY.

UNCOUPLING DEVICE.

1,169,829.

Specification of Letters Patent.

Patented Feb. 1, 1916.

Application filed July 2, 1914. Serial No. 848,540.

To all whom it may concern:

Be it known that we, ROBERT E. L. JANNEY and EDMUND P. KINNE, citizens of the United States, and residents of Chicago, county of Cook, and State of Illinois, and Alliance, county of Stark, and State of Ohio, respectively, have invented certain new and useful Improvements in Uncoupling Devices, of which the following is a specification.

Our invention relates to car couplers and has particular reference to a novel coupler operating device.

In the application of car couplers to passenger cars it is requisite that the knuckle lock shall be operated from the bottom, and that means shall be provided for operating such lock either from the car platform or from the side of the car. In our device the coupler may be operated either from the side of the car or from the car platform, each operation being independent of the other. This is preferable it being particularly desirable that the operation from the side of the car may be independent of the platform operating means inasmuch as if the operation from the side of the car required the actuation of the platform operating means, it would be difficult due to the necessity of actuating several levers, beveled gears, etc. It will also be noted that in our construction the levers on either side may be actuated without movement of the lever on the opposite side. This is due to the peculiar form of the eyes at the ends of the operating rods.

A further advantage is in that the coupler lock may be placed in lock-set position whereupon the operating handle at the side of the car or the handle on the platform may return to normal position, only a portion of the lock-lifting mechanism remaining elevated as an indicator of the condition of the lock.

The invention will be more readily understood by reference to the accompanying drawings, wherein—

Figure 1 is a front elevation of a car coupler having our novel operating means ap-

plied thereto. Fig. 2 is a plan view of a similar coupler. Fig. 3 is a longitudinal, vertical section through a car coupler and car platform showing the application of the operating means thereto, and illustrating particularly the facility with which the coupler may move forward or backward or swing sidewise without interfering with the lock operating mechanism.

Referring more particularly to the drawings it will be seen that beneath the car platform 10 are provided sills 11 to which is secured a carry iron 12 supporting a car coupler 13. Depending from the carry iron are brackets 14, having an open ended slot 15 therein, which open end is normally closed by bolts 15a. Depending from the coupler is a rod 17 the upper end of which engages the coupler lock (not shown), the lower end being provided with an eye 16 within which the end of a rod 18 engages, the engaging end being bent in the form of an S, as best shown in Fig. 2. The other end of the rod 18 is likewise bent into S shape and accommodates a transverse rod or rock bar 19 having a central eye 20 formed therein, as best shown in Fig. 2. This eye is seated in the concave portions of the S and is so arranged that it may move freely in a clockwise direction, as viewed in Fig. 3, but a movement in a counter clockwise direction will likewise move the rods 18 and 17. The rod 19 is seated in the recess 15 in brackets 14 and is adapted for horizontal sliding movement therein. The ends of the rod 19 are provided with eyes 21 vertically disposed with which the bent end of a hand operating rod 22 engages. This rod extends to the side of the car and is held by a bracket 23, the rod terminating in a handle 24. It will be seen that the rod 22 may be rotated by lifting the handle 24, thus causing a rotary movement of the rod 19; however the rod 19 may remain in the position assumed by such rotation and the rod 22 may return to its original position, due to the peculiar formation of the engaging portions of the rods 19 and 22. The opposite end of the rod 19 is engaged in a similar

manner by a rod 25 terminating in a bend 26, this rod being, however, provided with an angular extension 27 having an eye 28 therein, which eye is engaged by a rod 29 connected to a bell crank 30 keyed to a shaft 31, which shaft carries a beveled gear 32. This gear meshes with the similar gear 33 fast on post 34, the upper end of which is adapted to be engaged by the swinging lever 10 35, as is shown.

It will be seen that the handle 24 may be lifted to actuate the coupler lock without interfering with the rod 25 or the platform-operating mechanism; that after the lock 15 has been placed in lock-set position the operating handle 24 will return to its normal position, the rod 18, however, remaining in elevated position as an indication of the condition of the lock; that the platform operating mechanism may be used to lift the lock and that the rod 22 and handle 24 will not be moved during such actuation; that after the lock has been placed in lock-set position the platform operating rod may be 20 turned to normal, the rod 18 remaining elevated to indicate the condition of the lock. It will further be noted that the coupler is free to move forward or backward or to swing sidewise without interfering in any 25 manner with the operating mechanism or without possibility of the lock being accidentally operated due to such coupler movement.

It is obvious that modifications may be 30 made in the construction shown, and such modifications as are within the scope of our claims we consider within the spirit of our invention.

We claim:

40 1. In a device of the class described, the combination of a lock-operating rod extending longitudinally of the car and having an S-shaped bend in one end, a transverse rod having an eye, said first rod overlying and 45 engaging the eye in said second rod, whereby said rods are permitted relative movement through at least 90° but are positively rotatively connected in an opposite direction, said rods being supported at their 50 junction beneath the coupler with provision for freedom of movement relative to the support, substantially as described.

2. In a device of the class described, the combination of a coupler having a depending lock-operating rod, a longitudinal rod having a connection permitting oscillation between said lock-operating and said longitudinal rods, a transverse rod, said transverse rod being mounted for horizontal sliding movement in a longitudinal direction, and means extending to the side of the car and connected to said transverse rod for imparting movement to said rods, substantially as described.

3. In a device of the class described, the combination of a longitudinal rod having an S-shaped bend in one end thereof, a transverse rod having an eye engaging said S-bend and arranged to permit relative movement through at least 90°, said transverse rod being provided with eyes in its ends, and rods extending to the side of the car and engaging said transverse rod, the connection between said last named rods likewise permitting relative rotation through 75 at least 90°, substantially as described.

4. An uncoupling device for car couplers comprising a coupler-lock operating-rod extending longitudinally of the car, an endwise movable rock bar extending transversely of the car and connected intermediate of its ends to the coupler-lock operating-rod and provided at its ends with eyes, bearings for the rock bar, said bearings being mounted independently of the car coupler 80 and the rock bar being capable of endwise movement through said bearings, and operating-rods extending to the respective sides of the car and provided with eyes hooked into the respective eyes of the rock bar and 85 constituting rotative connections therewith, each of said rotative connections being positive in one direction but permitting limited rotation in the opposite direction.

5. In combination with a coupler, a lock 95 operating rod extending longitudinally of the car, a transverse rod having an eye in each end and near its middle, said longitudinal rod being connected to said intermediate eye by means of an S-bend, and rods 100 connected to the eyes in the ends of the transverse rod and providing a knuckle joint, said rods extending from said transverse rod to the side of the car, substantially as described.

105 6. An uncoupling device for car couplers comprising an endwise movable rock bar extending transversely of the car, a lock lifting crank arm carried by the rock bar and intermediate the ends of the rock bar, 110 the connection between the rock bar and the crank arm being such as to effect upward movement of the latter in one direction of rotation of the rock bar and to permit rotation of the rock bar in the opposite direction independently of the crank arm, and operating devices for the respective ends of the rock-bar, each operating device having a connection with the rock bar to effect rotation thereof in one direction and to permit rotation of the rock bar in the opposite direction independently of the operation of the operating device.

115 7. An uncoupling device for car couplers comprising an endwise movable rock bar extending transversely of the car, a lock lifting crank arm carried by the rock bar, the connection between the rock bar and the 120

- crank arm being such as to effect upward movement of the latter in one direction of rotation of the rock bar and to permit rotation of the rock bar in the opposite direction
- 5 independently of the crank arm, an operating device, and a connection between the rock bar and the operating device to effect rotation thereof in one direction by the operation of the operating device and to permit
- 10 rotation of the rock bar in the opposite direction independently of the operation of the operating device.
